(57) **CLAIM**

I claim the ornamental design for a plastic fence component, as shown and described.

DESCRIPTION

FIG. 1 is a front elevational view of a plastic fence component according to the present invention, with a remainder of a fence section, posts, and a gate shown in broken lines for environmental purposes only, and forming no part of the claimed design.

FIG. 2 is a front elevational view of the plastic fence component according to the present invention the rear view being identical thereto;

FIG. 3 is a top view of the plastic fence component according to the present invention, the bottom view being identical thereto;

FIG. 4 is a side elevational view of the fence component according to the present invention, the other side view being identical thereto; and,

FIG. 5 is a detailed cross-sectional side view of the plastic fence component according to the present invention, taken along lines 5—5 in FIG. 2.

The broken lines in FIGS. 1-5 are for environmental purposes only, and form no part of the claimed design.
